(57) **CLAIM**

The ornamental design for a shoe upper, as shown and described.

DESCRIPTION

FIG. 1 is a rear perspective view of a shoe upper showing my new design;

FIG. 2 is a rear view thereof;

FIG. 3 is a side view thereof; and,

FIG. 4 is an opposite side view thereof.

The broken lines immediately adjacent to the shaded area represent unclaimed boundaries of the design. The ten unshaded regions within the shaded area that are demarcated by broken lines form no part of the claimed design. The broken lines showing the remainder of the shoe are for environmental purposes only and form no part of the claimed design.
